UNITED STATES PATENT OFFICE.

ANDREW HANCOCK, OF BAKERSFIELD, CALIFORNIA.

LANTERN.

Application filed March 6, 1925. Serial No. 13,609.

This invention relates to improvements in signal devices and more particularly to an apparatus to be used in connection with lanterns or the like.

5 An important object of the invention is to provide a device of the above mentioned character whereby signal indicating means may be interchangeably positioned opposite the illuminated portion of a lantern or the like.

10 A further object of the invention is the provision of a signal apparatus of this character whereby intersecting traffic may be instructed as to procedure.

15 A still further object of the invention is to provide a device of this character whereby signal indicating means bearing signal characters may be alternately illuminated.

20 A still further object of the invention is the provision of a signal lantern which will be positive in operation, durable, simple in construction and inexpensive to manufacture.

25 Other objects and advantages of this invention will be apparent during the course of the following description.

In the accompanying drawings wherein like characters of reference are employed to designate corresponding parts throughout the same:

Figure 1 is a front elevation of the device embodying my invention showing the signal members in operative position,

35 Figure 2 is a side elevation of the same showing the signal members in reversed position,

Figure 3 is a rear elevation showing the device in inoperative position,

40 Figure 4 is a horizontal sectional view taken through the central portion of the device as shown in Figure 3,

Figure 5 is a perspective view showing a portion of the supporting frame, and

45 Figure 6 is a detailed view showing the construction of the movable signal members.

In the drawings, wherein for the purpose of illustration is shown the preferred embodiment of my invention, the numeral 10 generally indicates the base structure of a common form of lantern usually employed by watchmen at railroad crossings and the like. The upper portion of this lantern carries a bail or handle 11 pivotally secured to the lantern casing to permit carrying or swinging the same. When using a lantern of this character in connection with my

improved device 1 consider it desirable to provide an opaque shield 11' which may be constructed of asbestos or any suitable material and adapted to cover the upper portion of the lantern globe, as will be clearly apparent as the description progresses.

The description thus far has dealt with the construction of the conventional type of lanterns usually employed as a signal light for directing traffic and like usage.

My invention resides more particularly in apparatus to be employed in connection with lanterns of this or any preferred type for indicating more definitely the movement of traffic at crossings. This is accomplished by the provision of a supporting frame generally designated by the numeral 13 constructed of four vertical corner posts 14 secured at the lower extremities to the base

75 plate of the lantern. The upper extremities of these vertical posts are braced by a plurality of cross rods 15 forming a substantially rectangular frame. The lower portion of the frame is braced in a similar

80 manner by a plurality of cross rods secured substantially above the lower extremities of the vertical posts, these upper and lower cross rods also being adapted to serve as bearing shafts for operating members which

85 will be hereinafter more fully described.

An inner box-like casing 16 is formed about the frame 13 constructed of four signal plate frames 17. These frames are connected at the extremities to form the casing 90 and are adapted to slide vertically along the vertical corner posts of the supporting frame. A second somewhat larger casing 18 composed of signal plate frames 19 is movably positioned about the inner casing 25 and adapted to move telescopically in relation thereto.

These inner and outer casing members are provided with actuating handles 20 substantially U-shaped in formation and adapted to permit movement of the signal casing. The intermediate portions of the casing handles are preferably bent in arcuate form as at 21 so as to conform to the general contour of the lantern handle 11 and permit the same to be retained in an elevated position together with the lantern handle as clearly illustrated in Figure 1. It is thus obviously seen that one of the signal plate casings is permitted to remain opposite the illuminated section of the lantern while the other casing is elevated by means of its

handle. In order that these casings may be raised or lowered in an even and easily operable manner I consider it desirable to provide a pair of pulleys on each of the cross rods. The pulleys 22 rotatably mounted upon the front and lower cross rods are in vertical alignment and guide suitable cords or cables 23 connected to the upper and lower edges of the signal casing frame by means of eye-bolts 24. The outer casing is operated through similar mechanism mounted on the side cross rods.

The signal plate frames are preferably constructed of channel shaped bars to engage suitable transparent or translucent signal plates 25 preferably constructed of glass or similar material. These plates may be of different colors and in this manner indicate a particular signal, or they may contain letters indicating word signals as, for instance, the words "Go" and "Stop" shown on the signal plates in the drawings. In the latter type it is also preferable that the plates be of different colors thereby materially assisting the direction of the traffic and enabling pedestrians and vehicle drivers to recognize the signal at a substantial distance therefrom.

While I have shown the device in this particular form and used in connection with a lantern I contemplate numerous additional applications thereof, for instance, utilizing the apparatus in association with traffic or signaling devices employed at many intersections in cities and towns. Numerous forms of illuminating means may be used in connection with this apparatus and numerous means for operating the same may be designed to accommodate the particular application.

It is to be understood that the form of my invention herewith shown and described is to be taken as the preferred example of the same and that various changes as to the shape, size and arrangement of parts may be resorted to without departing from the spirit of the invention, or the scope of the subjoined claims.

Having thus described my invention, I claim—

1. A device for signaling comprising a rectangular supporting frame, means for mounting the said frame in position upon a lantern or the like, the said lantern being adapted to illuminate the lower portion of the frame only, an inner signal casing adapted to vertically slide along the supporting frame posts, an outer signal casing also adapted to slide vertically against the inner casing, handle members secured to the casings and adapted to elevate or lower the

same, rotatable members mounted upon the transverse beams of the supporting frames, cables trained over the rotatable members and connecting with the casings to balance the same, and transparent signal plates mounted in the frames of the casings for signaling purposes.

2. In combination with a lantern having its upper portion covered by an opaque shield, a supporting frame including vertical corner posts, horizontal cross rods secured to the upper extremities of the corner posts and adjacent the lower extremities thereof, a rectangular signal casing composed of four frame members adapted to slide upon the corner posts of the frame, an outer casing member of similar construction adapted to vertically slide in engagement with the inner casing, pulleys rotatably mounted upon the horizontal cross rods, cable members trained about the pulleys and connected with the casings to permit even operation of the same, handle members secured to the casings adapted to permit elevation thereof in association with the handle of the lantern, and transparent signal plates mounted in the casing frame.

3. In combination with illuminating means, a rectangular signal frame mounted in association with illuminating means whereby the lower portion of the frame only is illuminated, a plurality of casing members slidably mounted upon the said frame, means for raising and lowering the said casing members, means for permitting even operation of the said casing members, and transparent signal plates positioned in the casing frames.

4. A device of the character described comprising a rectangular supporting frame, means for mounting the said frame in association with an illuminating device, a box like casing slidably mounted about the said supporting frame, the said casing containing plates bearing letters indicating signal instructions, and means for readily adjusting the said casing relative to the said frame and illuminating device.

5. A device of the character described comprising a substantially rectangular supporting frame, means for securing the said frame in association with a lantern, box like signal casings vertically slidable about the said support frame, the said casings containing signal plates bearing signal instructions thereon, and means for sliding the casings and plates relative to the said frame and lantern.

In testimony whereof I affix my signature.

ANDREW HANCOCK.
